REFRIGERATION MECHANISM

Raymond G. Hilger, Chicago, Ill.

Application June 25, 1937, Serial No. 150,299

4 Claims. (CL 62—115)

The invention relates to refrigeration mechanisms and more particularly to improvements in expansion-type refrigerating systems.

In Patent No. 1,601,445 issued to George Hilger on September 28, 1926, a three-pressure multistage expansion refrigeration system is disclosed in which high-pressure refrigerant is expanded into a single header maintained at a constant intermediate pressure and subsequently expanded again through separate thermally controlled valves into a plurality of low-pressure evaporators. One object of the present invention is to provide an improved multistage expansion refrigeration system of this same general type but in which increased flexibility and effectiveness of operation of the system are had through the utilization of a novel arrangement for selectively maintaining an intermediate-pressure stage for the refrigerant flowing to a plurality of evaporators at either the same or different pressures for the several evaporators.

Another object of the present invention is to provide a plural evaporator refrigeration system including a multipressure expansion valve unit for each evaporator which successively decreases the pressure of the refrigerant in at least two stages but with the formation of a minimum of flash gas in the intermediate stage or stages of such expansion.

A further object of the invention is to provide a plural evaporator refrigeration system embodying an improved arrangement for defrosting any selected one of the evaporators without interrupting the operation of the other evaporators in the system and with a minimum loss in overall efficiency of the system.

The invention also resides in certain structural improvements in the expansion valve unit of the system.

Further objects and advantages of the invention will become apparent as the following description proceeds and the features of novelty which characterize the invention are pointed out with particularity in the claims annexed to and forming a part of this specification.

For a better understanding of the invention, reference may be had to the accompanying drawing in which

Figure 1 is a diagrammatic illustration of a refrigeration system embodying the invention.

Fig. 2 is an enlarged longitudinal sectional view of one of the expansion valve units included in the system shown in Fig. 1.

Fig. 3 is an enlarged longitudinal sectional view

of one of the three-way valves included in the systems shown in Fig. 1.

The present invention is particularly applicable to plural evaporator systems and accordingly, has been illustrated as embodied in a system including two separate evaporators 10 and 11. These evaporators may be mounted in separate heat insulated compartments or chambers and the system is such that they can be readily utilized to absorb heat loads of not only different quantitative value but also loads which vary irregularly with respect to each other. Consequently, a high degree of flexibility in the operation of the system may be had.

High-pressure liquid refrigerant may be supplied in the system from any suitable source, the one illustrated herein being a conventional compressor-condenser unit including a compressor 12 driven by a belt-connected electric motor 13. Compressed liquefiable gaseous refrigerant is discharged from the compressor outlet 14 into a conduit 15 through which it passes to an air-cooled condenser 16 in which the compressed gaseous refrigerant is liquefied upon the diminution in temperature thereof by the cooling air 25 passing over the condenser. The refrigerant thus liquefied in the condenser 16 is accumulated by gravity flow in a receiver 17.

Separate expansion valve units designated generally by the numerals 18 and 19 are associated with the respective evaporators 10 and 11 and serve to expand the high-pressure refrigerant into the associated evaporators upon diminution of its pressure in successive stages. It will be noted that the expansion valve units 18 and 19 are connected to the high-pressure receiver 17 in parallel relation by a supply conduit 20 and branch conduits 21 and 22. The expansion valve units are substantially identical in construction and consequently, a description of one of these units will suffice for both.

Upon reference to Fig. 2, it will be seen that the expansion valve unit 18 includes in general a main valve casing member 23 cored out to form a chamber 24, constituting an intermediate refrigerant pressure zone, and expansion valves 25 and 26 located respectively at the inlet and outlet of the chamber 24. The automatic expansion valve 25 throttles the high-pressure refrigerant from the receiver 17 to a selected substantially constant intermediate pressure in the chamber 24 while the valve 26 expands the intermediate-pressure refrigerant from the chamber 24 into the evaporator 10 in accordance with the thermal requirements of the evaporator.

In the preferred construction illustrated, the expansion valve 25 includes a valve element 21 carried by a stem 28 and disposed in an inlet passage 29 formed in the casing 23. This valve element cooperates with a complementary seat 5 formed in a hardened wear-resistant bushing 30 threaded in a transverse partition in the valve casing 23 to control the flow of refrigerant from the inlet passage 29 to the chamber 24. A disk-shaped pressure actuating member 31 exposed to the pressure of the refrigerant in the chamber 24 is secured to the lower end of the valve stem 28 so that the pressure of the refrigerant in the intermediate-pressure zone is utilized to move the valve element 21 to its closed position, this action being supplemented by a small compression spring 32 interposed between the top of the valve element and a removable cap 33 threaded in a suitable aligned opening in the top of the 10 casing 23. A second and larger compression spring 34 bears against the lower side of the pressure member 31 and tends to move the valve element 21 into open position. This latter spring 34 is mounted within a cup-shaped housing 35 detachably secured to the lower side of the casing 23 by cap screws 36, an imperforate flexible gasket 37 being interposed between the housing 35 and casing 23 to form a hermetic seal therebetween. The opening pressure exerted by the 15 spring 34 on the valve element 21 may be varied by a suitable adjusting screw 38 threaded in the lower end of the housing 35 and bearing against a disk 39 seated in the lower end of the helical compression spring. A removable threaded cap 30 40 prevents accidental contact with or change of position of the adjusting screw 38. It will thus be seen that the pressure of the spring 34 may be varied through the medium of the adjusting screw 38 in such manner as to counterbalance the opposed spring 32 and the pressure exerted 45 on the pressure actuating member 31 until the latter pressure reaches some predetermined minimum value at which point the spring 34 is overbalanced and the valve element 21 moved to closed position. The expansion valve 25 may 50 thus be readily adjusted to admit refrigerant to the intermediate-pressure chamber 24 whenever the pressure therein falls below some selected minimum value so that the intermediate pressure prevailing within the chamber 24 is maintained substantially constant. It will also be understood 55 that the intermediate pressures within the expansion valve units 18 and 19 respectively may be maintained at different selected, though constant, values which are best suited to the particular requirements of the associated evaporator.

The thermally controlled expansion valve 26 includes in general a spherical valve element 41 cooperating with an annular wear-resistant valve seat member 42 threaded in a suitable partition 60 in the casing 23 to control the flow of refrigerant from the chamber 24 to an outlet passage 43. The spherical valve element 41 is mounted in a complementary recess in the top face of a disk 44 carried on the top of a helical compression spring 45 which normally biases the valve element to closed position. It will be noted that the spring 45 is disposed within a bore 46 in a cylindrical extension 47 formed on the lower side of the valve 65 casing 23 and surrounds a boss 48 on a cylindrical plug 49 which is threaded in the lower end of the extension 47. An annular sheet metal spring retainer 50 surrounding the boss 48 in loose sliding engagement therewith maintains the lower 70 end of the spring 45 in position. Adjustment of 75

the spring pressure may be effected by shifting the retainer 50 axially through the medium of an adjusting screw 51 which contacts the bottom of the spring retainer and is threaded in the plug 49. The escape of gaseous refrigerant axially of the adjusting screw 51 is prevented by packing washers 52 held in position by a threaded gland 53. The outer end of the adjusting screw is protected by a cap 54 which is similar to the protective cap 40 and is threaded on the outer 10 end of the plug 49.

The operating mechanism for the valve element 41 of the expansion valve 26 comprises in general a pair of oppositely acting pressure elements shown in the form of the disk-shaped ends of 15 imperforate resilient metal bellows 55 and 56. The faces or ends of these bellows are connected by a spool-shaped actuating member or pin 57 made of thermal insulating material. It will be noted that the lower bellows 56 is exposed to the 20 pressure of the refrigerant in outlet passage 43 while the upper bellows 55 is disposed in a separate chamber 58 formed within a separable housing 59 attached to the valve casing 23 by cap screws 60. Pressure fluid is admitted to 25 the chamber 58 through an opening 61 therein and the actuating pin 57 may thus be made to move axially in accordance with the differential 30 between the refrigerant pressure prevailing in the valve unit outlet passage 43 and some external 35 variable pressure which is transmitted to the chamber 58. In the construction illustrated the pressure in the chamber 58 is caused to vary in accordance with changes in temperature at the outlet of the associated evaporator. For this purpose, a feeler bulb 62 (Fig. 1) of conventional 40 construction is clamped in heat exchange relation with the return line for the evaporator 10 and communication is had between the interior of the bulb and the chamber 58 through a feeler line 63. An inert gas is used to fill the bulb 62 so that its volume varies in accordance with 45 changes in temperature in the refrigerant return line for the evaporator.

In order that the refrigerant in the passage 43 45 shall not affect the temperature of the inert gas on the outer side of the bellows 55, a thermal barrier is placed between the chamber 58 and passage 43. For this purpose an annular portion of heat insulating material 64, such as felt 50 or the like, is interposed between the bellows 55 and 56, this portion of insulating material having a central opening through which the insulating spool 57 passes. In order to form a hermetic seal between the chamber 58 and the interior of 55 the valve casing 23 the bellows 55 and 56 are provided with annular laterally extending flange portions 55^a and 56^a, respectively, these flanges being clamped between the adjacent portions of the housing 59 and valve casing 23 with an annular spacer member 65 interposed therebetween. This spacer member may also be made of material having a low thermal conductivity, such as Bakelite. Thus, it will be seen that in the operation of the valve 26 the actuating spool 57 will 60 be shifted axially downwardly when the pressure within the chamber 58 exceeds that within the passage 43 by a predetermined amount which may be selectively varied by the adjustment of the balancing spring 45. Such a downward 65 movement of the actuating spool 57 causes an intermediate actuating member 41^a to move downwardly against the valve element 41 to shift the latter to open position. As the temperature 70 at the outlet of the evaporator 10 decreases due 75

to the admission of further refrigerant upon such opening of the valve 26, the pressure in the chamber 58 decreases correspondingly so that the valve element 41 is again permitted to move 5 to its closed position under the bias of the spring 45.

From the foregoing, it will be seen that a simple and compact expansion valve unit has been provided in which a single casing member serves 10 for both of the expansion valves and which is otherwise simplified in construction. In addition, it will be noted that the intermediate-pressure chamber 24 is of comparatively small volume and length, thus minimizing the formation of 15 flash gas therein as the refrigerant is throttled through the expansion valve 25. Thus, the advantages of accurate control of the temperature of the associated evaporator are had through the use of an intermediate-pressure stage but the 20 disadvantages resulting from the use of a large volume intermediate-pressure header or the like are avoided. In addition, the use of separate preliminary expansion valves for each evaporator makes possible a closer and more accurate control 25 of the associated evaporator temperature. In some installations, however, it is desirable to equalize the intermediate pressure in order to correlate the operation of the evaporator units in the system and for this purpose, a by-pass conduit 30 66 (Fig. 1) is provided which communicates with the intermediate-pressure chambers of the respective expansion valve units 18 and 19. A manually operable shut-off valve 66^a is interposed in this conduit so that the intercommunication between 35 the intermediate-pressure zones of the two units may be cut off at will. It will be understood that the conduit 66 serves as an effective means for conveying intermediate-pressure refrigerant from one valve unit to the other in case one of the 40 evaporators is heavily loaded so that insufficient refrigerant is supplied through the initial expansion valve therefor or in the event that its initial expansion valve becomes damaged or inoperative for any reason.

In the operation of the system described above, 45 high-pressure liquid refrigerant from the receiver 17 is expanded into the evaporators 10 and 11 through their associated expansion valve units 18 and 19. The quantity of refrigerant supplied to the evaporator 10 is controlled in accordance with its return line temperature through the medium of the feeler bulb 62 as described above and a similar feeler bulb 62^a disposed in thermal 50 contact with the return line for the evaporator 11, connected through a feeler conduit 63^a with the valve actuating mechanism in the unit 19, controls the flow of refrigerant to the evaporator 11 in a similar manner. The refrigerant vaporized in the evaporators 10 and 11 then flows 55 through the respective return lines 67 and 68 to the compressor inlet 69. This cycle is repeated and continued to maintain the evaporators at the desired respective temperatures.

An arrangement has also been provided for 60 effectively defrosting one or more of the evaporators while maintaining the remainder of the evaporator units in the system in operation. For this purpose, a conduit 70 is arranged to 65 convey hot gaseous refrigerant from the outlet 70 of the compressor 12 to the respective outlets 10^a and 11^a of the evaporators 10 and 11. The outlets of the evaporators may be connected either to their return lines 67 and 68 or to the 70 hot gas supply conduit 70 by three-way valves 75 71 and 72, the details of one of these valves be-

ing illustrated in Fig. 3. Thus, it will be seen that in the position of the valve illustrated in Fig. 3 the evaporator outlet 10^a communicates with the conduit 70 through a slot 73 in a rotatable valve element 74 movable by a manual operating handle 75. Upon clockwise rotation of this valve element through an angle of approximately 90° (as viewed in Fig. 3) the valve element cuts off communication between the conduit 70 and the evaporator outlet 10^a while connecting the latter to the return line 67. When the valve 71, for example, is shifted to connect the evaporator 10 with the hot gas supply conduit 70 and disconnect it from its return line 67, a flow of compressed hot gaseous refrigerant is had in a reverse direction through the evaporator, thus warming the same and effectively defrosting it. The refrigerant liquid forced out of the evaporator 10 due to this reverse flow of high-pressure gas may be utilized 15 in the other evaporator 11 by transferring the same from the expansion valve unit 18 to the expansion valve unit 19 through conduit 66 upon opening the valve 66^a. It will be understood that the evaporator 11 may be defrosted 20 at will by a similar manipulation of its associated three-way valve 72.

Although a particular embodiment of the invention has been shown and described in some detail for purposes of illustration, there is no 30 intention to thereby limit the invention to such embodiment but, on the other hand, the appended claims are intended to cover all modifications within the spirit and scope of the invention.

I claim as my invention:

1. In a three-pressure refrigeration system the combination with a source of high-pressure compressed and liquefied vaporizable refrigerant, of a plurality of low-pressure evaporators having 40 inlets and outlets; an expansion valve unit associated with each of said evaporators and connected in series relation between said source and the associated evaporator; each of said units including a valve casing defining an intermediate refrigerant pressure zone chamber, an expansion valve for controlling the flow of refrigerant from said high-pressure source to said chamber to maintain a selected substantially constant pressure therein, and a second expansion valve for governing the flow of refrigerant from said chamber into the associated evaporator in response to variations in the temperature of the refrigerant discharged from the evaporator; means connecting the outlets of said evaporators to said source in parallel relation, and means rendered operable and inoperable at will to equalize the pressures in said intermediate-pressure zone chambers.

2. A refrigeration system comprising, in combination, a compressor having an inlet and an outlet and supplying compressed vaporous refrigerant at a high pressure and temperature, a condenser in communication with said compressor outlet, a plurality of evaporators, means 65 including separate expansion valve units associated one with each of said evaporators for supplying refrigerant from said condenser to said evaporators, each of said units including a valve casing defining an intermediate-pressure zone 70 chamber having an inlet and an outlet passage and an independently operable pressure reducing valve element in each of said passages, means for returning vaporized refrigerant from the outlets of said evaporators to said compressor 75

inlet, means operable at will for cutting off communication between any selected one of said evaporator outlets and said compressor inlet and for establishing communication between the selected outlet and said compressor outlet thereby to direct a flow of hot gas reversely through the evaporator to defrost the same, and means operable at will to direct refrigerant from the intermediate-pressure chamber of the valve unit associated with said one evaporator to the intermediate-pressure chamber of another of said valve units during such reverse flow of refrigerant.

3. A refrigeration system comprising, in combination, a source of high-pressure compressed and liquefied vaporizable refrigerant, a plurality of low-pressure evaporators, individual valve means associated with each of said evaporators for reducing the pressure of refrigerant from said source in a plurality of successive stages

and supplying the same to the associated evaporators, and means operable at will to equalize the pressure of the refrigerant in a plurality of said valve means in an intermediate-pressure stage thereof.

4. In a three-pressure refrigeration system an expansion valve unit adapted to be interposed between a source of high-pressure liquid vaporizable refrigerant and a low-pressure evaporator comprising a valve casing member cored out to form an intermediate-pressure refrigerant chamber of small volume having inlet and outlet passages, an expansion valve in said inlet passage, a throttling valve element in said outlet passage, thermostatic means for moving said valve element in response to changes in temperature at a remote point, and means for thermally insulating said thermostatic element from the refrigerant flowing past said valve element.
